DESIGN FOR AN OIL BURNER

George Irving Carter, Teaneck, N. J., assignor to General Oil Heating Corporation, West New York, N. J., a corporation of New Jersey

Application November 4, 1938, Serial No. 81,121

Term of patent 14 years

To all whom it may concern:

Be it known that I, George Irving Carter, a subject of the King of Great Britain, being a citizen of the Dominion of Canada and a resident of Teaneck, in the county of Bergen and State of New Jersey, have invented a new, original, and ornamental Design for an Oil Burner, of which the following is a specification, reference being had to the accompanying drawing, forming part thereof.

On the drawing:

Fig. 1 is a perspective view of an oil burner embodying the new design;

Fig. 2 is a plan view of the oil burner shown in Fig. 1; and

Fig. 3 is a side elevational view of the oil burner.

I claim:

The ornamental design for an oil burner, as shown.

GEORGE IRVING CARTER.
